UNITED STATES PATENT OFFICE.

AARON KENT, OF ALLEGHENY, PENNSYLVANIA.

WINDOW.

No. 838,863.

Specification of Letters Patent.

Patented Dec. 18, 1906.

Application filed June 2, 1905, Serial No. 263,420.

To all whom it may concern:

Be it known that I, AARON KENT, a citizen of the United States of America, residing at Allegheny, in the county of Allegheny and 5 State of Pennsylvania, have invented certain new and useful Improvements in Windows, of which the following is a specification, reference being had therein to the accompanying drawings.

10 This invention relates to certain new and useful improvements in windows, and relates more particularly to a novel form of weather-strip adapted to be used in connection with the sashes thereof.

15 My improved weather-strip is particularly adapted for use in connection with a window the sashes thereof being constructed to be swung upon horizontal pivots without interfering with the usual method of raising and 20 lowering said sashes. My improved weather-strip as applied to the above-described character of window-frame is adapted to render a compartment weather and dust proof when said window is used in connection with said 25 compartment.

The primary object of the invention is to provide a weather-strip which will serve functionally as a lock for securing a window-sash in a vertical or upright position, also 30 serving to close the joints that exist between a pivotally-mounted window-sash and its slide-bars.

Another object of the present invention is to provide a weather-strip which will be positive in its action, simple and inexpensive in 35 its construction, and free from all danger of being broken from ordinary use.

The invention finally consists in the novel construction, combination, and arrangement 40 of parts, to be hereinafter more fully described and then specifically pointed out in the claim, and, referring to the drawings accompanying this application, like numerals of reference designate corresponding parts 45 throughout the several views, in which—

Figure 1 is a front elevation of a window-frame, illustrating a sash and one side of the frame in section. Fig. 2 is a detail perspective view of the sliding bar of the frame, 50 illustrating the side rails of a sash swung outwardly upon a horizontal plane. Fig. 3 is a vertical sectional view of a portion of a sash and sliding bar, illustrating my improved weather-strip. Fig. 4 is a bottom 55 plan view of a portion of a sash and sliding

bar. Fig. 5 is a cross-sectional view of the same, and Fig. 6 is a detail perspective view of my improved weather-strip.

In the accompanying drawings I have illustrated a window-frame 1, having upper 60 and lower sashes 2 and 3 mounted therein. The sashes 2 and 3 are pivotally connected by trunnions 4 to sliding bars 5, which are connected to the ordinary form of weighted sash-ropes 6, that are carried by the frame 1. 65

My invention resides in providing a novel form of weather-strip adapted to close the joint 7 existing between the side rails of the sashes and the sliding bars 5. The side rails 8 of the sashes are provided with vertically-disposed slots or grooves 9, extending from the bottom of said sash to the top thereof. The grooves 9 are preferably located near one edge of the sash, and in the sliding bars 70 slots or grooves 10 are provided which are 75 adapted to mesh or align with the slots or grooves 9 of the sash. In the slots or grooves 9 of the side rails 8 I mount my improved weather-strips, which are preferably constructed of a light and durable metal. 80 Each weather-strip consists of a strip of metal 11, having elongated openings 12 formed near its ends, said openings having straight sides and extending diagonally with respect to said strip. Extending into said 85 openings are studs or pins 14, carried by the side rails of the sash. The lower end of the strip 11 is bent outwardly, as indicated at 15, and the bottom edge of the sash and sliding bar is cut away, as indicated at 16, to 90 receive the outwardly-bent end 15 of the strip and permit of easy access being had to this end of the strip in order that it may be easily gripped when it is desired to operate the same. 95

In the present illustration I have shown the weather-strip as having two plies of material—that is, a piece of material being used and the edges bent upon themselves, as clearly illustrated in Figs. 5 and 6 of the 100 drawings; but I do not care to confine myself to this construction.

In Fig. 3 of the drawings I have illustrated the weather-strip in an unlocked position—that is, in such a position that the sash carrying the side rail 8 can be readily swung outwardly upon a horizontal plane. In order that the strip may assume this position, the sash is partially raised, said sash having been raised in order that a person may reach 105 110

under the lower edge of the sash and pull the weather-strip downwardly to the position illustrated in Fig. 3. When it is desired to close the sash 3 and lock the sash in a vertical position in engagement with its sliding bars, the lower end of the weather-strip is pushed upwardly, and as the same is mounted upon the studs or pins 14 of the sash and as the elongated openings 12 are diagonally disposed relative to the strip said strip will travel upwardly into the groove or slot 10 of the sliding bar and will positively close or break the joint existing between the side rails of the sash and its sliding supporting-bars. As the guides or parting-strips protect the joint formed between the sliding bars and the window-frame, the compartment in connection with which the window is used will be weatherproof and dustproof and an almost air-tight connection established between the different movable parts of the window. I do not care to limit myself to the form of pivotal connection used between the window-sashes and their sliding bars or to the means employed for elevating said sashes.

It is thought from the foregoing that the construction, operation, and advantages of the herein-described window will be apparent without further description, and various changes may be resorted to in the form, proportion, and minor details of construction without departing from the spirit of the in-

vention or sacrificing any of the advantages thereof. 35

What I claim, and desire to secure by Letters Patent, is—

The combination with a window-frame of grooved sliding bars, a window-sash having grooves on its edges registering with the grooves in the sliding bars, said window-sash being pivotally attached to said sliding bars and metallic strips having diagonal slots, said strips being each composed of a piece of material doubled on itself, said strips being arranged in grooves in the window-sash and said sash being provided with pins passing through the slots in the strips, the window-sash and sliding bars being cut away at the lower ends of said grooves and the ends of the strips being bent outwardly and resting in the cut-away portions of the bars and the window-sash, said strips when moved downwardly projecting below the lower edge of the sash, and when in this position resting entirely within the grooves in the sash, and said strips being adapted when the sash is lowered to contact with the frame and to be forced into the grooves in the sliding bars. 45 50 55

In testimony whereof I affix my signature 60 in the presence of two witnesses.

AARON KENT.
